UNITED STATES PATENT OFFICE.

HENRY O. SCHMIDT, OF NEW YORK, N. Y., ASSIGNOR TO SIMONS, BROTHERS & CO., OF PHILADELPHIA, PENNSYLVANIA.

DESIGN FOR A CANE OR UMBRELLA HANDLE.

SPECIFICATION forming part of Design No. 20,555, dated March 3, 1891.

Application filed February 6, 1891. Serial No. 380,514. Term of patent 3½ years.

To all whom it may concern:

Be it known that I, HENRY O. SCHMIDT, a citizen of the United States, residing in New York, in the county and State of New York, have invented and produced a new and original Design for Cane or Umbrella Handles, of which the following is a specification, reference being had to the accompanying drawing, forming part thereof.

10 In the drawing is shown a perspective view of a cane or umbrella handle illustrating my new design.

A is the shank, and extends upwardly into the head B, having the smooth or plain top C, slightly depressed. The head B is ornamented by a series of downwardly-extending ribs, like cords, terminating in a series of circular ribs on the shank portion A. The lower portion of the shank A is ornamented by vertical 20 ribs having the appearance of the ribs of the

head B extending below the horizontal ribs. The appearance is as if the horizontal ribs were tied about a series of vertical ribs, so as to reduce the diameter of the shank as compared with the head B. The lower part of 25 the shank A is finished by an annular band D of highly-ornamental work.

The handle may be made of any suitable material.

Having now described my design, what I 30 claim as new, and desire to secure by Letters Patent, is—

The design for cane or umbrella handles, substantially as herein described and shown.

In testimony of which invention I have 35 hereunto set my hand.

HENRY O. SCHMIDT.
